UNITED STATES PATENT OFFICE.

EMIL T. NEBEN, OF RIDGEWOOD, NEW JERSEY; MATHILDA GROPP NEBEN EXECUTRIX
OF SAID EMIL T. NEBEN, DECEASED.

MANUFACTURE OF RELIEF-ENGRAVED PRINTING CYLINDERS.

Application filed May 13, 1921. Serial No. 469,190.

To all whom it may concern:

Be it known that I, EMIL T. NEBEN, a citizen of the United States, and a resident of Ridgewood, in the county of Bergen and State of New Jersey, have invented new and useful Improvements in the Manufacture of Relief-Engraved Printing Cylinders, of which the following is a full, clear, and exact description.

10 The invention relates to molds for casting peripherally closed relief engraved printing cylinders, such as shown and described in the Letters Patent of the United States, No. 1,261,642, granted to me April 15, 1918.

15 The object of the present invention is to provide certain new and useful improvements in the manufacture of relief engraved printing cylinders whereby the printing cylinder is rendered absolutely true and even, and practically free of imperfections at the printing face to insure the subsequent making of perfect impressions when used in the art of continuous rotary printing.

20 Another object is to permit the manufacture of relief engraved printing cylinders in an exceedingly economical manner and to allow of varying the thickness of the metal of the printing cylinder for strength and 25 durability according to the use made of the printing cylinder.

25 In order to produce the desired result, the invention consists essentially in first producing an electrotype plate, bending the same into a cylinder with the printing face disposed exteriorly, placing the printing cylinder into a mold having a highly polished interior surface, then subjecting the interior surface of the printing cylinder 30 to a hammering action to force the printing face of the cylinder into intimate contact with the polished inner surface of the mold to render the printing face true and even.

35 The invention also consists in suitable means for applying a molten metal backing to the inner surface of the printing cylinder to give any desired thickness to the metal of the printing cylinder.

40 The invention in addition consists in providing suitable means for heating the mold preparatory to receiving the molten metal.

45 With these and other objects in view, the invention consists of certain novel features of construction, as hereinafter shown and

described and then specifically pointed out 55 in the claims.

A practical embodiment of the invention is represented in the accompanying drawings forming a part of this specification, in which similar characters of reference indicate corresponding parts in all the views.

50 Figure 1 is a face view of the electro-plate;

55 Figure 2 is an outline view of the apparatus for bending the electroplate into cylindrical shape;

60 Figure 3 is an end view of the printing cylinder with the contacting side edges soldered together;

65 Figure 4 is a similar view of the printing cylinder within the mold to be hammered into true and even shape;

70 Figure 5 is an enlarged sectional side elevation of the apparatus for providing the printing cylinder with a backing;

75 Figure 6 is a sectional plan view of the same on the line 6—6 of Figure 5; and

Figure 7 is a reduced end view of the 80 finished printing cylinder.

In order to produce the relief engraved printing cylinder, I proceed in detail as follows: A pen and ink, or a wash drawing is first made and matched on all sides when curved on a wooden roll. From this drawing is made a negative in line or half-tone 85 and printed on zinc or copper and etched in the usual manner. A plate thus prepared forms an original stock plate from which is made an electrotype 10, shown in Figure 1, having a raised printing surface 90 11. The electroplate 10 is placed between two protecting members 12 and 13 and is then passed through a bending machine having three cylinders 14, 15 and 16 to bend the electroplate into a peripherally closed relief 95 engraved printing cylinder 20, shown in Figure 3. The abutting edges of the cylinder 20 are soldered together either throughout the length of the joint or in several places to maintain the shape of the cylinder. 100

The cylinder 20 is next placed into a mold 21 having an exceedingly highly polished interior surface against which abuts the printing face 11 of the cylinder 20. The interior surface of the printing cylinder 20 is now subjected to a hammering action, 105 preferably by the use of an electric hammer, to force the printing face 11 into intimate

contact with the polished inner surface of the mold 21 to render the printing face true and even.

The printing cylinder 20, after being removed from the mold 21, is placed into a mold 30 with the printing face 11 in contact with the interior surface of this mold 30. The mold 30 is made in sections 31 connected with each other by hinges 32 to permit of conveniently opening and closing the mold. A locking device 33 of any approved construction is used to hold the sections 31 locked when in closed position. Within the mold 30 and spaced from the inner surface of the printing cylinder 30 is a tubular core 35 made in sections 36 having overlapping sides 37 to allow the sections 36 of the core 35 to expand and contract, as will be readily understood by reference to Figure 6. The inner surface of each core section 36 is provided with a number of vertically spaced wedges 40 each having a dovetail groove 41 into which fits a correspondingly shaped tongue 42 of a wedge 43 secured to a mandrel 44, preferably of tubular shape, and held centrally within the core 35. It will be noticed that by the arrangement described the pairs of wedges 40 and 43 coact with each other to expand or contract the sections 36 of the core 35 on moving the mandrel 44 upward or downward. The lower open end of the mandrel 44 fits onto a guide pin 45 engaging at its lower end a central opening 46 formed in a bottom or base plate 47 closing the lower end of the mold 30 and the core 35. The guide pin 45 is provided with a collar 48 seated on the upper surface of the bottom 47 to support the pin 45 in vertical position and centrally within the mold 30. The upper portion of the mandrel 44 is provided with a screw thread 50 in which screws a screw rod 51 having a smooth upper portion 52 mounted to turn in a bearing 53 arranged within the upper end of the core 35. The screw rod 51 is provided with a collar 54 supporting the bearing 53, and a retaining collar 55 is attached to the smooth portion 52 and is seated on the top of the bearing 53. The upper end 58 of the smooth portion 52 of the screw rod 51 is made polygonal for the application of a wrench or other tool to permit of turning the screw rod 51 with a view to move the mandrel 44 up or down according to the direction in which the screw rod 51 is turned. Thus when the screw rod 51 is turned in one direction the mandrel 44 is raised and the pairs of wedges 43, 40 move the sections 36 of the core 35 inward, and on moving the mandrel 44 downward the pairs of wedges 43, 40 move the sections 36 of the core 35 outward. Thus by the arrangement described the space 60 between the core 35 and the inner surface of the printing cylinder 20 can be increased and diminished and as this

space is filled with molten metal for forming a backing for the printing cylinder 20 it is evident that the backing will be of more or less thickness. The bearing 53 is provided with projections 65 preferably in the form of the heads of screws screwed to the bearing 53, the said projections 65 engaging openings 66 formed in the corresponding sections 36 of the core 35. Similar projections 37 are arranged on a bearing 68 held on the pin 45 and resting on the top of the collar 48 of the said pin 45. By the arrangement described the sections 36 of the core 35 are guided in their expanding or contracting movement and are not liable to be accidentally displaced.

Through the bottom 47 extend pipes 70 registering with the annular space 60, and the pipes 70 are connected by a pipe 71 with a vessel containing the molten metal for forming the backing for the printing cylinder 20. The core 35 is preferably protected by a covering 75 of pressboard. A closing ring 76 is seated on the top of the core 35 and the top of the printing cylinder 20 to close the upper end of the space 60 to prevent the discharge of molten metal from the space 60 at this end. From the foregoing it will be seen that the apparatus for providing the printing cylinder 20 with a backing can be readily opened and closed for the insertion and removal of the printing cylinder, and the sections 36 of the core 35 can be readily adjusted inward or outward to provide the printing cylinder 20 with a backing 74 of a desired thickness. Ring 76 may be provided with one or more suitable vents to permit the air to escape as the molten metal enters.

Having thus described my invention, I claim as new and desire to secure by Letters Patent:

1. In an apparatus for producing a relief engraved printing cylinder, a sectional tubular outer mold adapted to hold the printing cylinder with the printing face thereof in contact with the inner surface of the mold, a sectional tubular core within the said mold and spaced from the printing cylinder, manually controlled means extending through the center of said core and movable longitudinally thereof for expanding or contracting the sections of the said core to vary the space between the core and the printing cylinder, and means for passing the molten metal into the space between the core and the printing cylinder to provide a backing for the latter.

2. In an apparatus for producing a relief engraved printing cylinder, a sectional tubular outer mold adapted to hold a printing cylinder with the printing face thereof in contact with the inner surface of the mold, a sectional tubular core within the said mold spaced therefrom, a mandrel movable

longitudinally and centrally within the said core, coacting pairs of wedges on the said mandrel and core to expand or contract the same, and means for passing a molten metal 5 into the space between the core and the printing cylinder to provide a backing for the latter.

3. In an apparatus for producing a relief engraved printing cylinder, an outer cylinder 10 within which the engraved printing cylinder is placed, a sectional core arranged within the printing cylinder, a mandrel within said sectional core, and means on the mandrel and the sections of the core for 15 moving said sections to or from the inner face of said printing cylinder.

4. In an apparatus of the class described, an outer casing adapted to receive a printing plate, a core placed within said printing 20 plate, means movable longitudinally of said core for expanding or contracting said core so as to permit a space between the inner face of said plate and said core, and means

for passing molten metal in said space for providing a backing for said printing plate. 25

5. In an apparatus for producing a relief engraved printing plate, an outer cylinder within which the engraved printing plate is placed, the face of the printing plate bearing against the inner face of said cylinder, a core extending within said cylinder at spaced relation with the rear face of the printing plate, means extending within said core for contracting or expanding said core so as to increase or decrease the space between the core and the plate, means connected at the end of said cylinder for passing molten metal into said space so as to provide a reinforcing backing for said plate, means at the opposite end of said cylinder so as to form a closure for said space between the core and the plate to prevent the molten metal from escaping through that end of the cylinder. 35 40

EMIL T. NEBEN.
